Primary Examiner—Paula A. Mortimer**CLAIM**

The ornamental design for interconnecting detachable extended vision optical elements, as shown and described.

DESCRIPTION

FIG. 1 is an exploded front perspective view of an interconnecting detachable extended vision optical element showing my new design;

FIG. 2 is a front perspective view thereof, the broken line showing of the baseball cap is for illustrative purposes only and forms no part of the claimed design;

FIG. 3 is a front perspective view thereof; and,

FIG. 4 is a front perspective view in an alternate position.
